UNITED STATES PATENT OFFICE.

THOMAS H. KENVIN, OF GARY, INDIANA.

REGENERATOR CONSTRUCTION.

1,104,513.

Specification of Letters Patent. Patented July 21, 1914.

Application filed January 7, 1914. Serial No. 810,802.

To all whom it may concern:

Be it known that I, THOMAS H. KENVIN, a citizen of the United States, residing at Gary, in the county of Lake and State of Indiana, have invented certain new and useful Improvements in Regenerator Constructions, of which the following is a specification.

The present invention has reference to 10 certain improvements in regenerator constructions, and has reference particularly to the arrangement of the regenerators, and their combination with the furnace with which they are intended to operate.

15 It is found that during the operation of the regenerators they rapidly collect flue-dust and the like, which is carried over from the furnace during the campaign of heats, so that, after the furnace has been in 20 operation for some time, the checkerwork becomes clogged or obstructed by the presence of the flue-dust. For this reason it is necessary to clean out the checkerwork from time to time, and this necessitates a temporary shutting down or throwing out of commission of the regenerator. Furthermore, 25 it is necessary to rebuild the checkerworks from time to time, and, of course, this also necessitates a shutting down of the regenerator. Under ordinary circumstances, whenever 30 any one of the regenerators is thrown out of commission, the entire furnace arrangement must be shut down, for the reason that it has been customary to provide only the necessary or proper number of regenerators corresponding to the normal operation 35 of the furnace. For this reason, the operation of the entire furnace must be discontinued during the cleaning or reconstruction of a single regenerator.

The main object of the present invention is to provide an arrangement of regenerators, such that, when a regenerator must be thrown out of commission either for 45 cleaning or repair, another regenerator may be brought into commission in its place, so that the operation of the furnace may proceed uninterrupted. This arrangement will very greatly increase the load efficiency of 50 the furnace, and consequently its tonnage during the year. In this connection, another object of the invention is to so arrange or relate the regenerators as to occupy the floor or ground space in a highly 55 efficient manner, so that no additional space will be required for placing into effect the

arrangement to which the present invention relates.

Another object of the invention is to provide a valve arrangement such that the several regenerators may be readily controlled and brought into or thrown out of commission, thereby greatly facilitating the handling of the entire arrangement.

Other objects and uses of the invention will appear from a detailed description of the same which consists in the features of construction and combinations of parts hereinafter described and claimed.

In the drawings: Figure 1 shows a plan view of an arrangement of furnace and regenerators embodying the features of my invention; Fig. 2 shows a vertical section on the line 2-2 of Fig. 2, looking in the direction of the arrows; Fig. 3 shows a section taken on the line 3-3 of Fig. 1, looking in the direction of the arrows; and Fig. 4 shows a section taken on the line 4-4 of Fig. 1, looking in the direction of the arrows.

In the several figures, the regenerators are shown as associated with an open-hearth furnace 5. The gas regenerators are designated 6 and 7, and the air regenerators are designated 8, 9, and 10. The regenerators 8 and 10 may be designated the normal air regenerators, while the regenerator 9 is a substitute air regenerator which can be thrown into commission in place of either of the regenerators 8 or 10. It is preferred that all three of the air regenerators be grouped together opposite the central portion of the furnace, and that the gas regenerators 6 and 7 be located alongside of the air regenerators 8 and 9. With this arrangement, all five of the regenerators can be conveniently grouped within a space or width substantially the same as the length of the furnace itself, so that the regenerator 9 simply serves to fill or occupy a space which would otherwise be unoccupied. At the same time by grouping the regenerators in this manner the regenerator 9 may be substituted for either of the regenerators 8 and 10 with equal facility and without the necessity of providing unduly long connections or passageways.

The gas supply pipe connections are designated 11 and 12 and the stack or flue is designated 13. The connections 14, 15, 16, 17, and 18 are all adapted to place the various regenerators in communication with the stack or flue, while the connections 19 and

20 are adapted to place the gas regenerators 6 and 7 in communication with the gas supply connections 11 and 12 respectively. A valve member 21 is provided between each 5 of the gas regenerators and the corresponding connection 19 or 20, these valve members being so constructed that they will place their respective regenerators either in communication with the flue or stack, or in 10 communication with their respective gas connections. A valve 22 is provided in each of the connections 15, 16 and 17, for the purpose of controlling the communication of the corresponding air regenerator with 15 the stack or flue, or with the air supply connection underneath.

The rear end of each gas regenerator communicates by means of a passageway 23 with a vertically extending passageway 24, which, 20 in turn, communicates by means of a horizontal passageway 25 with the end of the furnace. The rear end of each of the regenerators 8 and 10 communicates by means of a connection 26 with a corresponding 25 passageway 27 beneath the end of the furnace, and each of the passageways 27 communicates with a pair of vertically extending passageways 28, which, in turn lead into a passageway 29 which leads into the end of 30 the furnace.

From the arrangement thus far described, it will be apparent that gas may be delivered, 25 through either of the gas regenerators into the corresponding end of the furnace, burned gases in the meantime flowing through the other gas regenerator to the flue or stack, and that, on the other hand, air may be delivered through either of the air regenerators 8 and 10 to the corresponding 40 end of the furnace, burned gases in the meantime passing through the other air regenerator to the flue or stack. In other words, the valve arrangements are such that the desired periodical reversal of flow may 45 be secured through either of the regenerators above considered.

The rear end of the intermediate or auxiliary air regenerator 9 may communicate by means of the connections 30 and 31 50 with either of the connections 26. The valves 32 and 33 are provided in the connections 30 and 31 respectively, and the valves 34 and 35 are provided between the regenerators 8 and 10 and their respective 55 connections 26.

From the foregoing it will be seen that the regenerator 9 may be substituted for either of the regenerators 8 or 10. For example, if it is desired to shut down the regenerator 8, the valves 34 and 33 may be closed, leaving the valves 32 and 35 open. This will throw the substitute regenerator 9 into commission in place of the regenerator 8, the regenerator 10 continuing to operate 5 as before. On the other hand by closing the

valves 32 and 35 and opening the valves 33 and 34, the regenerator 9 may be substituted for the regenerator 10, the regenerator 8 continuing to operate in the normal manner. Of course, when the substitute regenerator 9 is in operation, its valve 22 will be periodically shifted or reversed to control the flow of air through the regenerator to the furnace, or to allow the flow of burned gases from the furnace through the regenerator to the flue or stack. 75 75

The valves 32, 33, 34, and 35 are conveniently illustrated as damper valves which may be manipulated through the medium of cords 35^a operating over the rollers 35^b, as 80 best shown in Fig. 4. However, it will be apparent that any other suitable valve arrangement may be adapted.

Another feature of my invention has reference to the provision of a receptacle or 85 pocket for the removal of slag and the like, which may be carried over from the furnace during its operation. For this purpose, each of the passageways 26 is extended out some distance beyond the vertical passageways 90 28, so as to provide a pocket 36 at the extreme rear end of the passageway 26. The floor of this pocket may be made to slant toward the rear, so that slag and the like will collect at the rear end in the pocket 36, 95 where it may be conveniently removed from time to time. It will be noted also that the forward end of the passageway 26 is carried upward some distance to provide a weir 37, so as to largely, if not entirely, prevent the 100 carrying over of slag from the passageways 28 into the regenerator.

I desire to call particular attention to the fact that, by reason of the usual length of an open hearth furnace, and by reason of the 105 customary practice of placing the regenerators opposite the ends of the furnace, there is generally left a considerable space or distance between the air and gas regenerators, and opposite to the central portion of the 110 furnace. I wish to point out the fact that, in the present arrangement, I have availed myself of the presence of this open space for the accommodation of the auxiliary regenerator 9, so that said regenerator may be 115 accommodated without the necessity of moving the customary and usual regenerators farther apart than the usual custom. Furthermore, by locating the auxiliary regenerator in the above mentioned position, the same 120 is so placed that it can relieve the two air regenerators with equal facility, thereby enabling it to perform the function of either of said regenerators without the necessity of providing unduly long or tortuous passageways. It will be noted in this connection that, at the point where the passageways 30 and 31 are brought together, their rear walls are curved or bent inward at the point 28, so 125 as to assist in directing the air or gases for 130

the regenerator 9 in either direction with equal facility.

While I have herein shown and described only one particular arrangement of furnace and regenerators, the same including the open hearth furnace, still I do not limit myself to this arrangement, except as I may do so in the claims, but include within the scope of my invention any other equivalent arrangement of regenerators, or equivalent combination of regenerators and furnace, such as a heating furnace, for example.

I claim:

1. The combination with a furnace of a regenerator opposite to each end of the same, and an auxiliary regenerator between both of said regenerators and opposite to the body of the furnace, of a connection from each of the first mentioned regenerators to the corresponding end of the furnace, connections from the auxiliary regenerator to each end of the furnace, and valves for substituting the auxiliary regenerator for either of the first mentioned regenerators.
2. The combination with a furnace, a flue, and a source of air supply, of a regenerator opposite to each end of the furnace, a connection from one end of each regenerator to the corresponding end of the furnace, a connection from the other end of each regenerator to the flue and to the source of air supply, an auxiliary regenerator between both of said regenerators and opposite to the body of the furnace, connections from one end of said auxiliary regenerator to both ends of the furnace, a connection from the other end of the auxiliary regenerator to the flue and to the source of air supply, valves for controlling the connections of all of said regenerators either to the flue or to the source of air supply, and valves for controlling the connections from all of said regenerators to the furnace.
3. The combination with an open hearth furnace, a flue, and a source of air supply, of a regenerator opposite to each end of the furnace, a connection from one end of each regenerator to the corresponding end of the furnace, connections from the other end of each regenerator to the flue and to the source of air supply, an auxiliary regenerator mounted between said regenerators and opposite to the body of the furnace, connections from one end of said auxiliary regenerator to both ends of the furnace, connections from the other end of the auxiliary regenerator to the flue and to the source of air supply, valves for controlling the connections of all of said regenerators either to the flue or to the source of air supply, and valves for controlling the connection of each of said regenerators to the furnace.
4. The combination with an open hearth furnace, a flue opposite to the central portion of the same, and a source of air supply,
- 5 of a regenerator opposite to each end of the furnace, a connection from each of said regenerators to the corresponding end of the furnace, a connection from the other end of each of said regenerators to the flue and to the source of air supply, an auxiliary regenerator between both of said regenerators and opposite to the central portion of the furnace and opposite to the flue, connections from one end of the auxiliary regenerator to both ends of the furnace, connections from the other end of the auxiliary regenerator either to the flue or to the source of air supply, valves for controlling the connection of each of said regenerators either to the flue or to the source of air supply, and valves for controlling the connection of each of said regenerators to the furnace.
6. The combination with an open hearth furnace and a battery comprising an air regenerator and a gas regenerator adjacent to each end of the furnace, of a stand-by regenerator between both of said batteries of regenerators and opposite to the central portion of the furnace, connections from the furnace end of the stand-by regenerator to the furnace ends of the adjacent stand-by regenerators, connections from the flue end of the stand-by regenerator to the flue ends of the adjacent battery regenerators, and valves in all of said connections.
7. The combination with an open hearth furnace, and a battery consisting of an air regenerator and a gas regenerator extending at right angles to the furnace and adjacent to each end thereof, of a stand-by regenerator between the adjacent battery regenerators and extending at right angles to the furnace opposite to the central portion thereof, connections from the furnace end of the stand-by regenerator to the furnace

ends of the adjacent battery regenerators, connections from the flue end of the stand-by regenerator to the flue ends of the adjacent battery regenerators, and control valves in all of said connections.

8. The combination with an open hearth furnace and its batteries of regenerators adjacent to its ends, each battery comprising an air regenerator and a gas regenerator, of a stand-by regenerator opposite to the central portion of the furnace and between

the adjacent air regenerators, connections from the furnace end of the stand-by regenerator to the furnace ends of the air regenerators, connections from the flue end of the stand-by regenerator to the flue ends of the air regenerators, and valves for controlling all of said connections. 15
